TOOL FOR APPLYING FUSE LINKS TO
FUSED CUTOUTSDavid C. Hubbard, Centralia, Mo., assignor to
A. B. Chance Company, Centralia, Mo., a corporation of Missouri

Application February 12, 1947, Serial No. 728,122

9 Claims. (Cl. 294—19)

1

The present invention relates to tools for applying fuse links to fused cutouts, and is particularly concerned with tools adapted to be used with devices of the exposed fuse link type.

One of the objects of the invention is the provision of an improved tool adapted to hold a fuse link in such position that it may be readily controlled under all conditions, and so that it cannot sway due to wind or other causes, in order that it may be quickly and safely engaged with the contacts of an open type fused cutout, regardless of the position in which the contact fingers of the cutout are arranged.

Another object of the invention is the provision of an improved tool for applying fuse links to a fused cutout which is adapted to be used with the same facility, whether the contact fingers of the fused cutout be arranged horizontally, vertically or at an angle to these positions.

Another object of the invention is to eliminate the hazards which are encountered with the devices of the prior art in which the fuse link dangles from a prong type disconnect stick or similar device, so that the links are not under complete control of the operator, frequently falling off the stick, and when so dangling from a tool of the prior art the links are not adaptable to application to cutout arms which approach a horizontal position for the fuse link.

Another object of the invention is the provision of a tool of the class described which is adapted to protect the operator's face, and particularly his eyes, from the flying fragments and from the flash which may result if a short circuit condition exists at the time when the fuse is being applied to the cutout on an energized circuit.

A further object of the invention is the provision of an improved device of the class described which will eliminate the necessity for the repairman going to the nearest switch or circuit breaker to isolate the circuit before it is re-fused, and then, after re-fusing the cutout, again traveling to the circuit opening device to reclose the circuit, and returning a second time to inspect the re-fused cutout, the present device being applicable directly to the re-fusing of a cutout without isolating the circuit.

Another object of the invention is the provision of an improved tool for the application of fuses to fused cutouts which maintains the fuse unit under a predetermined tension, but holds it in such manner that the annular shoulders at each end of the fuse unit are in position to be engaged by the arms of the fused cutout and in such manner that the tool may be manipulated after the fused unit is engaged with the arms of the fused cutout and the tool may be readily released from the fuse unit, leaving it on the cutout.

Another object of the invention is the provision of an improved tool of the class described which may also be used for removing fuses from

2

a fused cutout, which is adapted to be manufactured at a low cost, which is sturdy, simple, and which presents a high factor of safety for the user, irrespective of the way in which the contacts of the fused cutout may be arranged.

Other objects and advantages of the invention will be apparent from the following description and the accompanying drawings, in which similar characters of reference indicate similar parts throughout the several views.

Referring to the drawings, of which there are two sheets,

Fig. 1 is a side elevational view showing the tool in connection with a standard fuse unit or fuse link.

Fig. 2 is a front elevational view taken from the right of Fig. 1.

Fig. 3 is a rear elevational view taken from the left of Fig. 1.

Fig. 4 is a view in perspective, showing the arrangement of the tool when carried by a universal pole and provided with a fuse link which is to be applied to a cutout of the fused type.

Fig. 5 is a side elevational view showing the first step in the use of the tool in securing the fuse link to the movable arm or contact finger of the cutout.

Fig. 6 is a similar view showing the next step in the application of the fuse link, which comprises the tensioning of the movable arm of the cutout and the application of the upper end of the link to the fixed arm.

Fig. 7 is another similar view showing the positions of the parts after the upper hook of the tool has been removed from the upper end of the link, and the operator is about to remove the lower end of the tool from the lower end of the link.

Fig. 8 is a fragmentary elevational view showing the other side of the supporting fixture carried at the top of Fig. 1.

Fig. 9 is a fragmentary plan view showing the contact fingers at the end of a fused cutout arm to which the link is to be applied.

Referring to Figs. 4 to 7, the present tool is indicated in its entirety by the numeral 10, and it is preferably so arranged that it may be mounted upon an operating pole 11 of the universal type, which is adapted to be used with a multiplicity of different tools. In some embodiments of the invention the present tool may be mounted upon a separate pole of its own, but even in such case it is preferably so arranged that it may be adjusted at different angles to the pole.

The operating pole 11 includes an elongated wooden pole 12 which is provided at its upper end with a ferrule or fixture 13 having a cylindrical socket for receiving the wooden pole 12. The fixture 13 is secured on the pole 12 by means of a plurality of rivets passing through the pole and fixture, and the fixture includes an axially ex-

tending flange 14 provided with a centrally located threaded bore for receiving the threaded wing bolt 15 which is preferably provided with an annular clamping flange 16.

The bolt 15 projects from the face of the flange 14 which is located substantially diametrically across the end of the ferrule 13, and the face 17 of flange 14 is provided with a plurality of radially extending ribs and grooves surrounding the shank of bolt 15.

Referring to Figs. 1 to 3 and 8, the tool 10 is provided with a supporting member 18 having a substantially circular body 19 provided with a face 20 which is complementary to the face 17 in that it has complementary and radially extending ribs and grooves on the face 17. The body 19 of the supporting member 18 has an inwardly extending slot 21 which is adapted to pass the shank of the screw bolt 15 so that the screw bolt may have its shank located in the central, partially cylindrical portion 22 of the slot 21. In this position the supporting member 18 may be rotated to any desired angular position in which its ribs and grooves will fit the ribs and grooves on the flange 14, and may be secured in that position by means of the clamping screw bolt 15. Thus the tool may be supported at any of a plurality of different angles on the operating pole 11.

The supporting member 19 for the tool 10 preferably has on its side opposite to the face 20 a partially annular thrust surface 23 for engagement with the thrust flange 16 on the clamping screw bolt 15. It also has a laterally projecting lug 24 which preferably extends oppositely to the slot 21, and which is provided with a through bore 25 by means of which the tool 10 may be supported upon this member.

Lug 24 is located toward one side of the supporting member 18, that is, the right side, for example, as seen at the top of Fig. 1, so that the body 19 of this member will not interfere with other parts of the device when the other parts are rotated on the supporting member.

The tool 10 preferably comprises a pair of metal members 26 and 27 which are supported by, and spaced from each other by an insulating member 28. The insulating member 28 so supports the fuse link that it is not shorted out during its application to a cutout. This is necessary, since a short-circuit might exist on the line or device which is being fused, and the metal members 26 and 27 which support the fuse link must be insulated from each other in order that the fuse may be interposed in the circuit rather than some other conducting member, and thus fuse protection is provided by the device during the application of the fuse.

The second purpose of the insulating member 28 is to shield and protect the operator's face and eyes from fuse particles and from the flash of a resulting arc in the event a short circuit or a faulty condition exists which would cause the fuse to rupture. To fulfill this purpose the insulating member 28 preferably comprises a partially cylindrical shield of laminated phenolic material, such as an indurated fibre, which is impregnated and covered with a phenolic condensation compound.

The shape of this shield or insulating member 28 is preferably partially cylindrical for the reason that it is desirable that the shield partially surrounds the fuse link, and such a shield may be economically made out of a section of a tube. In other embodiments of the invention the shield

may, however, take different shapes and need not necessarily be cylindrical.

The shield 28 is provided with a pair of straight edges 29, 30, and at its ends it preferably is beveled off, the beveled end portions being indicated by 31 and 32. The upper metal member 26 may consist of a rigid metal casting having an elongated body portion 33 which is provided with a pair of apertures 34 on its flat lower end for receiving the rivets 35 which pass through this end and through the shield 28 and secure the metal member 26 to the shield in axial position.

The body 33 of the upper member 26 may taper toward its upper end and may have a longitudinally extending reinforcing rib 36. At its upper end it may have a laterally projecting lug 37 provided with a plane surface 38 which engages the plane surface 39 on the lug 24 of the supporting member 18.

Through bore 40 is provided in the lug 31 which registers with the bore 25, both these bores receiving the rivet 41 by means of which the supporting member 18 is secured to the upper metal member 26 in such manner as to permit relative rotation between these parts on an axis which is substantially at right angles to the axis of the clamping screw bolt 15 of the universal pole 11.

Thus the tool 10 is supported for rotation on two axes at right angles to each other, so that it is capable of a substantially universal adjustment with respect to the operating pole 11. One of these adjustments, that is, the one provided by the rivet 41, may be utilized while the tool is being manipulated at the end of the pole 11 as the rivet 41 holds the supporting member 18 and upper metal member 26 frictionally against each other so that rotation may still occur if sufficient rotative force is applied by manipulating the pole.

A spring washer 42, located between the head of the rivet 41 (Fig. 1) and the lug 24, maintains a constant pressure between these parts, and provides a predetermined friction against rotative movement between them.

The upper metal member 26 extends upwardly, and toward the right in Fig. 1, from the lug 31, and is provided with an arm 43 which has a horizontally extending hook formation 44 at its end. This hook has a pointed end 45 and a relatively shallow groove or depression 46 adapted to receive the ring or loop 47 which is carried by the end of the standard fuse link.

The width of the pointed end portion 45 and the hook 44 is such that this hook may be received in the narrow end portion 48 of the ring 47 on the fuse link. Thus the upper end of the fuse link in Fig. 1 may be secured on the hook 44, but it should be noted that the present tool may be adjusted to any position in which the hook 44 may be located horizontally with respect to the other end of the tool, or even below the other end of the tool.

The metal member 27 at the other end of the insulating shield 28 is preferably made of resilient material, such as spring brass or spring copper or spring bronze, in order that it may place a predetermined tension on the fuse link being installed. Thus member 27 consists of a relatively wide strip of this spring material which is relatively thin.

The strip includes an attaching portion 49 which may be bent to partially cylindrical form to fit inside the partially cylindrical shield 28. A pair of registering through bores 50 are pro-

vided in the strip 27 and the shield 28 for receiving the rivets 51 by means of which this strip is fixedly secured to the lower end of the shield 28.

From its attaching portion 49 the spring strip 27 extends downwardly and rearwardly with an easy bend at 52, and it is provided with a substantially U-shaped portion 53 which terminates in a downwardly and forwardly extending, substantially straight arm 54. The straight portion 54 is provided with an upwardly curved portion forming a lower groove 55 which is located forwardly of the shield 28 by an amount which is at least as much as the forward location of the hook 44.

In order to provide for the support of fuse links of different length, the groove 55 may be located still farther forwardly of the shield 28, as shown in Fig. 1, so that a longer fuse link would involve the arm 54 being bent farther downwardly while still maintaining the link in a central position with respect to the shield, but spaced therefrom.

From the grooved portion 55 of the arm 54 this metal strip is then bent diagonally forwardly and downwardly, providing a downwardly extending portion 56. This end portion 56 is provided with a slot 57 which is of sufficient width so that the two fingers 58 which comprise the end portion 56 may be located on either side of the lower ring 59 of a fuse link, when this ring has its attaching portion located in the slot 57.

The slot 57 extends into the arm 54 to the point 60 just beyond the groove 55, and thus the lower end of the fuse unit may have its ring engaged in the forked end of the resilient member 27.

The resilient member 27 is initially bent to extend downwardly at a greater angle than that shown in Fig. 1, so that when the fuse unit is attached, the fuse link is under a predetermined tension which holds its rings in engagement with the hooks 44 and 56. Thus the fuse link does not dangle as it does in the devices of the prior art, and it may be held in any position, vertical, horizontal, or angular, and even inverted, if necessary, during its application to the cutout.

The fuse link or unit 61 may consist of any standard type of fuse link. The one selected for illustrating the invention comprises a pair of flexible metal cable portions 62, 63 joined to the rings 47 and 59 respectively. The upper ring 47 usually has the narrow upwardly extending portion 48 which is intended to receive the laterally projecting prong of a disconnect stick, while the round portion of the ring 47 is made of larger size in order to pass the head which is carried by this prong.

The lower ring 59 is usually round, and both of these rings are formed of suitable wire and have their parallel end portions 64, 65 clamped in a ferrule member 66 with the end 67 of the cable 60 between the end portions. This metal ferrule is brought into firm conducting contact and clamping position with the rings 59 and 47 and their respective cables by flattening the cylindrical portion 68 of the ferrule and also producing an elongated depression or slot 69 in one of its sides which forms an inwardly extending rib which forces its way into the braided cable and anchors it securely in the ferrule; at the same time, the compression anchors the ends of the rings in the ferrule.

A similar ferrule and anchoring arrangement is indicated at 70 for the lower ring 59.

Each of these ferrules is also provided with a radially extending flange 71 having a partially

spherical surface 72 on the side opposite to the ring. The flange 71 has an enlarged aperture 73 for cables 62 or 63, thus permitting a limited universal adjustment of the ferrules 66 and 70 with respect to the axis of the cable. It is the partially spherical surfaces 72 which are adapted to engage the contact arms of the cutout which is to be fused.

The flexible cables 62 and 63 extend into an insulating tube 74 comprising a laminated member impregnated with a phenolic condensation compound, and the ends of the cables 62 and 63 are joined in the tube by being soldered to a fusible section of a predetermined metal which is adapted to melt upon the application of a predetermined amount of current.

Metal ferrules 75 are located at each end of the tube 74 for guiding the cables 62, 63, and at one end of the tube 74 the cable 63 is surrounded by a compression spring 76 which is compressed between the ferrule 75 and a ferrule 77 which is clamped on the cable 63 in the same manner as shown at 69. The compression spring 76 is under a predetermined initial compression so that when the fuse ruptures it assists in drawing the cable out of the lower end of tube 74.

Referring to Figs. 4 to 7, these views illustrate one way of using the tool in re-fusing a cutout of the fused type. Such cutouts may be of any desired construction, but the one which is selected to illustrate the invention is mounted upon a bracket 78 which surrounds and clamps a porcelain insulator 79.

The insulator 79 has sockets in its ends in which metal fixtures are anchored for supporting the fixed arm 80 and the movable contact arm 81. The movable contact arm 81 may be itself resilient, or it may comprise a pivotal mounting in the housing 82 which is provided with spring means for urging the arm 81 downward.

Connectors 83 and 84 are provided on the cutout for connection to the circuit which is to be fused, but these connectors and the arms 80 and 81 are insulated from each other by the porcelain insulator 79 so that the current must pass through the fuse.

Both of the arms 80 and 81 are provided at their outer ends with one or more contact fingers 85 which form a V-shaped opening 86 in conjunction with the arm 80 or 81. The direction of pull on a fuse link between the arms 80 and 81 is such that the tension which is placed upon the link by the spring-pressed arm 81 tends to pull the link farther into the groove 86.

The method of operation and mode of use of the tool is as follows: When the fused cutout has its movable arm located below, then the fuse link may be arranged upon the tool as shown in Fig. 4. The tool is carried by the universal pole 11 extending downwardly but outwardly from the pole at an angle, and the link 74 has its upper ring carried by the hook 44 and its lower ring 59 carried by the resilient arm 27.

The shield 61 should be rotated until it is located between the eyes of the operator and the link 74 so as to protect the operator from flying particles of the fuse and from the flash which would result from a rupture of the fuse.

Referring to Fig. 5, the link 74 is then brought into a position with its lower cable portion 63 adjacent the movable or resilient contact arm 81 of the cutout. The cable section 63 is brought against the side of the arm 81, after which the tool assembly and link is moved outwardly of the

arm until the cable 63 is engaged in one of the V-shaped grooves 86 between arm 81 and contact finger 85.

An upward pull which is placed upon the fuse link by means of the pole will bring the lower ferrule 70 into engagement with the lower side of the contact arm 81 at the partially spherical surface 72. Then the operator pushes upwardly on the pole and so manipulates the pole that the upper cable section 62 engages the side of the fixed contact arm 80 on the cutout. The tool is then so manipulated that the cable section 62 slides outwardly on the side of the fixed contact arm 80 until cable section 62 engages in a V-shaped groove 86 of a contact 85 on the upper arm 80.

The parts are then in the position of Fig. 6, and as the operator lowers the operating pole 11 the spring pressure of the lower contact arm 81 of the cutout will tension the fuse link against the fixed arm 80. As previously stated, this tension tends to draw the cable sections 62 and 63 more tightly into the V-shaped grooves 86 of the cutout arms.

As contact is made between the fuse link and the second arm 80 of the cutout, if the cutout is energized it is possible that the fuse might be ruptured due to an existing fault. With the devices of the prior art, the lineman has no protection against such rupture of the fuse, and present practice makes it necessary to deenergize the circuit before it is fused. With the present invention, it is not necessary to deenergize the circuit, since the rupture of the fuse is shielded from the person and eyes of the operator by the shield 28.

This saves a great deal of time on the part of the operator, as the prior art devices require him to make a trip to the nearest switch or circuit breaker to isolate the circuit which is being re-fused and return to the cutout location to re-fuse the cutout. Then with the prior devices and practices he must travel again to the circuit opening device to re-close the circuit and return a second time to the fused cutout to inspect the re-fused cutout. All of these trips are eliminated by using the present tool and methods of re-fusing.

After the fuse link has engaged both the lower and upper contacts of the cutout, as shown in Fig. 6, the operator may move the tool 10 downwardly, but the upper ring 47 of the link will not move downwardly, and will be held in the same position projecting upwardly from the upper arm 80, as shown in Fig. 7. Thus the downward movement of the tool 10 will result in the removal of the hook 44 from the upper ring 47, and during this motion the lower spring 27 on the tool will flex upwardly.

Then the tool will be in the position of Fig. 7, and it is only necessary for the operator to move the tool upwardly while the resilient arm 27 is relieved of its tension. Then the tool may be moved backwardly from the lower ring 59, and the slot 57 will slide off the lower ring, freeing the tool entirely from the link, which continues to be held by the arms 80, 81 of the cutout.

It should be noted that there is no danger of pulling the link off the arms 80 and 81 while the tool is being freed from the links, because the pull of the tool in becoming free of the ring only tends to pull the link more tightly into the V-shaped grooves 86 of the arms 80, 81.

In some cases, the resilient or spring biased contact arm of the cutout may be in a higher

position than the stationary arm. In such case it may be desirable to reverse the position of the fuse link on the tool 10. Initial contact with the cutout should always be made to the spring-biased cutout arm so that the fuse link and resilient arm may then be pulled toward the stationary arm of the cutout.

The present tool may be used for installing fuses irrespective of the position in which the contact arms of the cutout happen to be. Since the fuse link is initially tensioned by the tool, it does not dangle as it does with the devices of the prior art, and, by virtue of the pivotal connections to the pole, the fuse link may be arranged in any desired position, horizontal, vertical, or at an angle.

In any event, the pole and shield may be so turned that the shield is interposed between the face of the operator and the fuse link, so that if the fuse is ruptured, he will be protected from flying particles of the fuse, and his eyes will be protected from the flash of the resulting arc.

A great deal of time may be saved by the use of this tool, because the operator may safely re-fuse circuits while they are energized, and may, of course, inspect the installation of the fuse immediately upon removal of the tool.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States is:

1. A tool for the installation of flexible fuse links which comprises an elongated insulating pole, a fuse link supporting member carried by said pole, said supporting member including an intermediate insulating portion and a fuse link engaging member at each of its ends for engaging with the members located at the ends of a standard fuse link, the said fuse link supporting member being adjustably mounted on the end of said insulating pole whereby it may be moved into substantial alignment with the contact arrangements of a fused cutout assembly preliminary to the application of the fuse link to the latter, the said movable mounting including pivotal arrangements on axes extending transversely to each other, giving a universal adjustment to the fuse link supporting member.

2. A tool for the installation of flexible fuse links which comprises an elongated insulating pole, a fuse link supporting member carried by said pole, said supporting member including an intermediate insulating portion and a fuse link engaging member at each of its ends for engaging with the members located at the ends of a standard fuse link, said insulating portion comprising an insulating shield adapted to be interposed between the operator and the fuse link during its installation to protect the operator from the results of a rupture of the fuse link during installation.

3. A tool for installing flexible fuse links on fuse link assemblies which comprises means for mounting the tool upon an insulating pole, said tool including a central elongated insulating portion and a pair of metal members, one extending from each end of said insulating portion, one of said metal members comprising a rigid hook for engagement with the loop at the end of a flexible

fuse link, and the other of said metal members comprising a resiliently urged hook for engaging the loop at the other end of said flexible link, said latter hook placing a predetermined tension on the fuse link to prevent its dangling and permit its being applied in any desired position, said insulating portion including an insulating shield to be interposed between the fuse link and the operator.

4. A tool for installing flexible fuse links on fuse link assemblies which comprises means for mounting the tool upon an insulating pole, said tool including a central elongated insulating portion and a pair of metal members, one extending from each end of said insulating portion, one of said metal members comprising a rigid hook for engagement with the loop at the end of a flexible fuse link, and the other of said metal members comprising a resiliently urged hook for engaging the loop at the other end of said flexible link, said latter hook placing a predetermined tension on the fuse link to prevent its dangling and permit its being applied in any desired position, said insulating portion including an insulating shield to be interposed between the fuse link and the operator, said shield comprising a curved insulating member subtending an arc between the operator and the fuse link to produce a predetermined area of protection.

5. A tool for installing flexible fuse links on fuse link assemblies which comprises means for mounting the tool upon an insulating pole, said tool including a central elongated insulating portion and a pair of metal members, one extending from each end of said insulating portion, one of said metal members comprising a rigid hook for engagement with the loop at the end of a flexible fuse link, and the other of said metal members comprising a resiliently urged hook for engaging the loop at the other end of said flexible link, said latter hook placing a predetermined tension on the fuse link to prevent its dangling and permit its being applied in any desired position, said means for securing to an insulating pole comprising a slotted metal member for receiving a clamping screw bolt, whereby it may be secured at any of a plurality of different angles, said slotted metal member having a pivotal connection to the first mentioned hook on an axis extending transversely to said clamping screw bolt.

6. A tool for applying fuse links to a fused cut-out assembly comprising an insulating shield comprising a section of a tubular member adapted to extend about a portion of the fuse link, said tubular section supporting at one end a rigid metal member which extends axially and has a transversely extending grooved arm for engagement with the loop of a fuse link, said tubular section supporting at its other end a leaf spring which extends axially and is transversely bent and provided with a grooved formation at its end for engagement with the other loop of a fuse link, whereby the fuse link is placed under sufficient tension to hold it on the tool, and means for mounting said tool upon an insulating pole.

7. A tool for applying fuse links to a fused cut-out assembly comprising an insulating shield comprising a section of a tubular member adapted to extend about a portion of the fuse link, said tubular section supporting at one end a rigid metal member which extends axially and has a transversely extending grooved arm for engagement with the loop of a fuse link, said tubular

section supporting at its other end a leaf spring which extends axially and is transversely bent and provided with a grooved formation at its end for engagement with the other loop of a fuse link, whereby the fuse link is placed under sufficient tension to hold it on the tool, and means for mounting said tool upon an insulating pole, said means comprising a supporting member having a substantially circular flange provided with an

10 inwardly extending slot adapted to receive a clamping screw bolt, said flange having its face provided with radial ribs and grooves for engagement with a complementary member on the pole, said supporting member being pivotally secured for tight frictional pivotal movement on said rigid metal member whereby the fuse link may, when supported on the tool, be adjusted universally to extend in the direction in which the contacts are arranged on a fused cutout assembly when the operator is in position to install the fuse link.

20 8. In a tool for applying fuse links to a fused cut-out assembly, a supporting body comprising an elongated, curved, insulating shield adapted to be interposed between the operator and the fuse unit, said shield being provided at one end with a resilient leaf spring having a forked and hook shaped end for engaging inside the ring of a standard fuse unit, and said shield carrying at its opposite end a substantially rigid hook member

25 for hooking in the ring at the opposite end of a standard fuse unit, said rigid hook being provided with an aperture transverse to the fuse unit, a pintle in said aperture, and a supporting member pivotally mounted on said pintle, whereby the

30 angularity of the fuse unit may be adjusted with respect to the supporting member into any of a multiplicity of different positions rotatively of said pintle.

35 9. In a tool for applying fuse links to a fused cut-out assembly, a supporting body comprising an elongated, curved, insulating shield adapted to be interposed between the operator and the fuse unit, said shield being provided at one end with a resilient leaf spring having a forked and hook shaped end for engaging inside the ring of a standard fuse unit, and said shield carrying at its opposite end a substantially rigid hook member

40 for hooking in the ring at the opposite end of a standard fuse unit, said rigid hook being provided with an aperture transverse to the fuse unit, a pintle in said aperture, and a supporting member pivotally mounted on said pintle, whereby the angularity of the fuse unit may be adjusted with respect to the supporting member into any of a multiplicity of different positions rotatively of said pintle.

45 10. In a tool for applying fuse links to a fused cut-out assembly, a supporting body comprising an elongated, curved, insulating shield adapted to be interposed between the operator and the fuse unit, said shield being provided at one end with a resilient leaf spring having a forked and hook shaped end for engaging inside the ring of a standard fuse unit, and said shield carrying at its opposite end a substantially rigid hook member

50 for hooking in the ring at the opposite end of a standard fuse unit, said rigid hook being provided with an aperture transverse to the fuse unit, a pintle in said aperture, and a supporting member pivotally mounted on said pintle, whereby the angularity of the fuse unit may be adjusted with respect to the supporting member into any of a multiplicity of different positions rotatively of said pintle, said supporting member having an

55 attaching flange provided with a slot for receiving a screw bolt, whereby the supporting member may be attached to a universal pole provided with a complementary flange and screw bolt for adjustment of the supporting member at any of a multiplicity of different angles on an axis transverse to said pintle.

DAVID C. HUBBARD.
